UNIFORM COAT

Augusta Eberle, North Hollywood, Calif.

Application August 5, 1948, Serial No. 147,951

Term of patent 14 years

(Cl. D3—4)

To all whom it may concern:

Be it known that I, Augusta Eberle, a citizen of the United States and resident of the city of North Hollywood, county of Los Angeles, State of California, have invented a new, original, and ornamental Design for Uniform Coat, of which the following is a specification, reference being had to the accompanying drawings, forming a part thereof, in which:

Fig. 1 is an elevational view of the front of a uniform coat, showing my design;

Fig. 2 is an elevational view of the back of the garment of Fig. 1.

I claim:

The ornamental design for a uniform coat, substantially as shown.

AUGUSTA EBERLE.
